UNITED STATES PATENT OFFICE.

AUSTEN H. FOX, OF NEW YORK, N. Y.

MAGNETIC APPARATUS FOR RAILWAYS.

1,162,468.

Specification of Letters Patent. Patented Nov. 30, 1915.

Original application filed March 6, 1909, Serial No. 481,780. Divided and this application filed March 2, 1914. Serial No. 821,890.

To all whom it may concern:

Be it known that I, AUSTEN H. FOX, a citizen of the United States, residing at New York city, in the county of New York and State of New York, have invented certain new and useful Improvements in Magnetic Apparatus for Railways, of which the following is a specification.

This invention relates to means for giving an indication on a railway vehicle by means of a pre-arranged condition of the roadway, and it relates more particularly to apparatus of this kind in which the running rail acts between control points as an armature for a magnet carried by the vehicle, there being suitable means provided at such control points for differentiating the magnetic action and releasing the vehicle magnet.

This application is a division of the application for my Patent No. 1,088,814, dated March 3, 1914, which was a continuation of a prior application, Serial No. 423,139, filed March 25, 1908, wherein the preferred means for differentiating the normal magnetic running rail consisted in locating non-magnetic sections at the control points, and when said control points were to be differentiated at will, in providing a magnetic by-pass bar which when operatively positioned alongside of the non-magnetic rail section, would counteract the effect thereof and hold the car magnet attracted.

Such a combination involves the use of moving parts in the roadway, and it is the principal object of my present invention to avoid the use of such moving parts. This I accomplish by employing an electromagnet in the roadway adjacent to or associated with the running rail. The said magnet and its connections may be so arranged as to accomplish additional objects as will appear.

In the accompanying drawings, Figure 1 represents a diagrammatic sectional view showing a portion of a railway and vehicle provided with my improvements. Fig. 2 represents a transverse section including a diagram of the track-magnet controlling circuit.

10, 19 are the running rails, 13 is the vehicle, and 14 is an electromagnet on said vehicle, which may be termed a "detector" since its condition of attraction or otherwise with respect to the running rail represents

the prearranged condition of the running rail at control points. For convenience I have shown this magnet on the body of the vehicle, although its preferred position would be on the truck. This magnet is constantly energized by a circuit including wires 15, 16, 17 and a battery 18. 19 is a switch for interrupting said circuit when desired. Preferably this magnet has two spools located in a plane transverse to the line of the running rail, and 20 are its pole pieces. 21 is a spring sufficiently strong to elevate said magnet when the latter comes over a control point where the magnet ceases to be attracted, and 22, 23 are the contacts of a switch controlled by the stem which carries the magnet, and adapted to be closed by the elevation and opened by the depression of the magnet; the said switch being located in a circuit including the wire 17, 75 battery 18, wire 24, and a suitable device which I have represented as a bell 25 for giving an indication as to the position of magnet 14. Any of the well-known devices may be employed, such as audible or visible 80 signals, air-brake control, etc., the functions of all of which are comprehended under the expression "giving an indication".

In Fig. 2 I have represented a section of one of the running rails 10 and a section of another rail 30 mounted alongside thereof, as constituting the pole pieces of a track magnet 31 located under the respective pole pieces 20 of the car magnet 14. The circuit of the track magnet includes a battery 32 85 and a pole-changer 33 whereby its pole pieces may be made of the same polarity as those of the car magnet, or of opposite polarity.

Fig. 1 represents the attracted condition 95 of the car magnet 14 when it is over the normal rail 10 between control points. When it comes over a track magnet 31, as shown in Fig. 2, if the polarity of the latter is opposite to that of the car magnet said 100 car magnet will be held attracted and no indication will be given on the vehicle. This is the clear or safe condition of the roadway. If the polarity of the track magnet has, by a shifting of the pole-changer 33, been made 105 the same as that of the car magnet, the latter will be repelled and an indication will be given on the vehicle by the ringing of the bell 25 (or the opening of an air-brake pipe, etc.). This is the danger or stop condition 110

of the roadway. The magnet 14 is preferably self-restoring so that when it again comes over the normal rail it will be attracted downwardly thereby and automatically open the circuit of the bell 25.

Various changes from the above arrangement may be made without departing from the spirit of my invention.

I claim,—

- 10 1. The combination of a railway having a magnetic running rail, a vehicle thereon having a magnet adapted to be attracted by said rail between control points, and a track magnet at the control point adapted to influence said vehicle magnet.
- 15 2. The combination of a railway having a magnetic running rail, a track magnet, one of the poles of which is composed of a section of said rail, the other being positioned

alongside of the same, and a vehicle on said 20 railway having a magnet provided with correspondingly positioned pole-pieces, and adapted to be influenced by said track magnet.

3. The combination of a railway having a 25 magnetic running rail, a vehicle thereon having a magnet adapted to be attracted by said rail, a track magnet associated with said rail and adapted to attract or repel the vehicle magnet, and a pole-changer in the circuit of said track magnet.

In testimony whereof I have hereunto set my hand in the presence of two subscribing witnesses, this 27th day of February, 1914.

AUSTEN H. FOX.
